5 Claims. (CL. 90—11)

1

This invention relates to the process herein-
after disclosed by which novel forming rolls of the
type employed in rolling mills may be produced.

This invention is a division of applicant's co-
pending application Serial No. 537,124, filed May
24, 1944.

The forming rolls of this invention are par-
ticularly adapted to impart the final or finished
shape to metal bars, such as reinforcing bars and
the like. In applicant's continuation-in-part ap-
plication Serial No. 537,125, filed May 24, 1944,
now Patent No. 2,377,980, issued June 12, 1945,
and its parent application Serial No. 501,553, filed
September 8, 1943, there is disclosed and claimed
a new and improved reinforcing bar for concrete,
which has a generally round cross-sectional shape
and is provided with oppositely disposed sets of
lugs with the lugs on one side inclined in one
direction and the lugs on the opposite side in-
clined in a reverse direction. The reinforcing
bar of the construction referred to is extremely
advantageous in use as a reinforcing bar but its
production by commercial methods, such as by
rolling operations, has presented various inher-
ent difficulties which have prevented its manu-
facture until the rolls and the process of pro-
ducing them, constituting this invention, had
been conceived and reduced to practice.

It is an object of this invention to produce im-
proved pairs or stands of finishing rolls of the type
referred to for forming bars, such as reinforce-
ing bars, having oppositely disposed sets of in-
clined or spirally arranged lugs which extend
substantially throughout 180° of the circumfer-
ence of the bar, and particularly to provide a new
and improved method by which such rolls may
be made.

A still further object is that of producing high-
ly efficient rolls which may be manufactured
and maintained at relatively low cost and which
are useful in producing the new and improved
reinforcing bar referred to.

Inasmuch as the bars of the type referred to
include in their construction lugs which extend
substantially entirely around the bar and which
at the same time are disposed at an angle to the
longitudinal axis of the bar, difficulty was en-
countered in providing forming rolls of charac-
ter and shape that would satisfactorily produce
such bars by the usual type of rolling operation.

To form a bar of this type, the forming rolls
must have deep, substantially semicircular
grooves extending circumferentially thereof, and,
in addition, angularly disposed lug-forming
grooves formed in the metal at the sides and

2

base of the semicircular grooves, which latter
grooves must also extend throughout the major
portion of 180° of the entire circumference. The
requirements of the rolls so constructed are such
that they cannot be formed by any practical com-
mercial method herefore employed for pro-
ducing such rolls, wherefore it was not until the
applicant had succeeded in applying the present
novel procedure and had conceived and construct-
ed the novel rolls of this invention that commer-
cial production was possible.

One of the difficulties which had to be met in
constructing the rolls, resides in the fact that the
character of the bar and of the forming rolls is
such that a particular structural relationship
must be provided between the rolls and the bar
in order to permit the forming rolls, during the
bar-forming operations, to free themselves of the
bar without wiping or destroying the lug forma-
tion on the bar after the lugs have been formed.
This problem was made more acute by the fact
that such freeing of the roll and bar requires that
the forming portions of the roll which move in
an arc are in engagement with lugs which are
moving in a straight line and, in addition, are be-
ing subjected at the same time to a drawing or
elongating operation which is productive of a
variation in the linear velocity of the bar leaving
the rolls with respect to the angular velocity of
the forming rolls. The solution of this problem
involves an understanding of the action which
takes place, and it has been found that there is
a limit as to the height of the lugs that can be
utilized on bars of any given diameter and, in ad-
dition, that the angularity of the leading side of
each of the lugs in relation to the pass-diameter
of the forming rolls (hereinafter defined) and the
height of the lug being formed are also limited.

Another problem which has been met by the in-
vention of applicant's copending application re-
ferred to, is that presented by the existence of
twisting components that are developed during
the rolling operation by the forming contact be-
tween the angularly disposed faces on the rolls
and corresponding faces on the lugs, which forces
tend to produce a twisted and distorted bar if the
force is not adequately offset. In one form of the
present invention the rolls are constructed so that
the opposite sets of lugs on the bars are oppo-
sitely disposed as to angularity, whereby the
twisting forces so exerted act to offset each other,
with the result that a satisfactory straight bar is
produced without undue strain or wear on the
rolls.

Another object of this invention is to produce

improved rolls of the character referred to, having such form that the steam or water, normally pocketed in passes having projections extending at right angles to the line of rolling, will be permitted to escape during the rolling operation so as to eliminate spalling and consequent damage to the rolls and bars being rolled.

A further object of this invention is to produce rolls of the type referred to, by first forming the desired number of circumferential pass grooves extending around the rolls, and thereafter producing a series of spirally disposed lug-forming grooves in the pass groove or grooves to be utilized by means of a tangentially disposed rotary tool or hob placed in the pass groove and on which there is provided a plurality of spirally disposed groove-cutting elements, and thereby forming the grooves by causing the hob and the roll to rotate at the proper relative speeds.

It is a further object of this invention to form one roll of each pair by means of a hobbing tool of the type referred to, having the cutting elements disposed on a spiral of one hand and forming the other roll of the pair by the use of a hobbing tool having cutting elements of the opposite hand, and in this manner to form a pair of rolls to form lugs developing opposed or offsetting twisting components of force during the rolling operation.

It is a further object of this invention to produce rolls of the type referred to, which have lug-forming grooves of such construction as to their depth and as to the angularity of their leading side that they will form the lugs as desired and at the same time pass freely from the lugs without wiping or in anywise damaging the lugs so formed.

It is a further object of this invention to produce rolls which are free from sharp corners or edges, whereby they are capable of long life without suffering unusual damage or undue wear, and which, by means of the hobbing tools, may be produced by a highly practical and inexpensive procedure.

These and other objects not specifically enumerated are contemplated for this invention, as will readily appear to one skilled in this art as the following description proceeds. In the following description of one illustrative embodiment of the invention, reference will be made to the accompanying drawings, in which—

Figure 1 is a side elevational view of a pair of rolls constructed in accordance with this invention.

Figure 2 is a cross-sectional view showing the rolls and an associated bar being processed thereby.

Figure 3 is an elevational view showing one of the rolls in the process of manufacture.

Figure 4 is a plan view of the roll and the associated hob illustrated in Figure 3.

Figure 5 is a fragmentary view of a section of the bar produced by the rolls of this invention.

Figure 6 is a view similar to Figure 5 but showing the bar after the bar has been rotated 90° on its axis.

Figure 7 is a cross-sectional view taken on the line 7—7 of Figure 6 and looking in the direction of the arrows.

Figure 8 is a view similar to Figure 6 showing a bar of slightly different construction, in that the sets of lugs on opposite sides of the bar have their ends out of alignment.

Figure 9 is a cross-sectional view taken on the line 9—9 of Figure 8 and looking in the direction of the arrows.

Figure 10 is an enlarged, fragmentary, cross-sectional view showing the construction of one of the lugs of a bar produced by the rolls of this invention; and

Figure 11 is an enlarged, fragmentary, perspective view, partly in cross-section, showing one of the lug-forming grooves of the rolls of this invention.

By referring to the drawings, it will be noted that the rolls produced according to the present invention are illustrated as embodied in a two-high rolling mill comprising uprights 10—10 of a roll stand and a pair of rolls 11 and 12, respectively, journaled in the uprights and driven by any suitable means (not shown).

The rolls 11 and 12 are each provided with a series of circumferential pass grooves 13 which are so disposed on the rolls, respectively, that each of the grooves of upper roll 11 cooperates with corresponding grooves on the lower roll 12, whereby a series of bar-forming pass openings are provided between the rolls. The rolls are maintained in spaced relation, as indicated at 14, so as to provide a space on opposite sides of each of the grooves 13 to accommodate the metal of the bar which is extruded laterally during the rolling operation so as to form a pair of diametrically disposed, longitudinally extending ribs on the bars.

Each of the grooves of the upper roll 11 is provided with a series of equally spaced lug-forming grooves 15 which are cut on a spiral path into the side and base metal of the groove. Similar lug-forming grooves 15 are provided on the lower roll 12, but in the form of the invention illustrated in Figure 1, the grooves 15 are spiraled in the opposite direction. Although lug-forming grooves are illustrated in Figure 1 in only one of the sets of pass grooves 13, it is to be understood that each of the sets to be employed for bar-rolling operations is to be similarly constructed.

The pass grooves 13 may be formed in the rolls by any conventional method by the use of suitable mechanism, and after the rolls are so grooved they may be further processed in the manner illustrated in Figures 3 and 4.

From these figures of the drawings it will be noted that a turntable 20 may be utilized, having centrally mounted thereon a chuck 21 provided with centering holding screws 22—22 for engagement with the depending bearing portion of the roll. The roll is thus centrally mounted and is adapted to be rotated with the turntable on the central axis of the roll.

The lug-forming grooves are next formed by means of a hob 25 which, as shown in Figure 4, is mounted for tangential engagement with the roll at the location of the groove 13 being processed. The hob is preferably constructed as shown in Figure 4, that is to say, it is provided with a plurality of cutting elements 26 projecting radially therefrom and arranged to exert their cutting effect in a spiral path. The hob in this form is mounted in suitable means (not shown) for rotating the same and at the same time advancing the hob bodily toward the axis of the roll being cut.

If exact specifications are to be maintained as to the pitch of the lugs on the bar to be formed, consideration must be given to the elongation of the bar which is effected during the rolling operation, in relation to the inherent shrinkage of the metal of the bar during the cooling thereof. In those instances where the draft is sufficient to

cause the elongation of the bar to be greater than the shrinkage, then the pitch of the lug-forming grooves on the rolls must be made correspondingly smaller. The hob is so constructed that a predetermined number of lug-forming grooves will be cut in the pass groove 13 of the roll, with the correct spacing between each of the lug-forming grooves so cut, whereby the action of the hob can be carried out while the roll is being rotated a plurality of times to the extent necessary to finish the cutting operation.

If desired, the turntable 20 and the hob can be independently driven, provided suitable synchronizing mechanism is utilized to maintain the rotation of each in proper relationship. On the other hand, in those instances where the driving force is not too great, the turntable may be left free to derive its rotary motion through the driving action imparted by the hob during the cutting operation. Furthermore, means must be provided, either manual or otherwise, for advancing the hob bodily toward the axis of the roll, whereby the depth of the lug-forming grooves will be increased as the cutting action progresses.

In making one roll of a pair of rolls, such as the upper roll 11, for instance, a hob 25 is employed which has its cutting elements disposed on a spiral of one hand involving a rotation of the roll during the cutting action in the corresponding direction. In cutting the other roll, however, a hob having its cutting elements arranged in a spiral of the other hand will be utilized, which will involve the rotation of the roll in the opposite direction. Instead of rotating the roll in the opposite direction, of course, the hob could be rotated in the opposite direction from that employed in cutting the first roll, but it is preferable in both instances to rotate the hob so that its cutting elements pass downwardly during the cutting stroke, so as to force all of the metal chips downwardly and out of the path of the cutting elements. The direction referred to may be described as clockwise in the illustration of Figure 3.

Referring now to Figure 11, it will be particularly noted that the lug-forming grooves in the roll are provided with inclined lug-forming side faces 31 which preferably terminate in a rounded fillet-forming surface 32 at the location of the base of the lug. Inasmuch as the angularity of the side of the lug is limited as to its steepness or its approach to the vertical in instances where wiping or unwanted damage is to be avoided, the maximum angle that can be employed is represented in the drawings as the angle G, which is the angle of the inclined surface with respect to the vertical. This angle is marked on the lug in Figure 10 and on the groove in Figure 11.

It has been found that for a bar of any given diameter it is desirable to limit the height of the lug for any given angularity of the lug in order to avoid wiping and damage during the rolling operation. The applicant has devised a formula for determining the height of the lug, which formula is as follows:

Lug height $B = (.0464 \times \text{nominal diameter of bar}) + .020$ inches in which the nominal diameter of bar is the diameter of the plain round equivalent in weight of the nominal size bar.

Example for 1 1/4 inch nominal size

1 1/4 inch square nominal size=
1.410 inch diameter equivalent round
wherefore

Lug height $B = (.0464 \times 1.410) + .020$
or .065 + .020, or .085 inch.

In addition, the applicant has worked out a formula by which to determine angle G in any particular case, which formula is as follows:

Angle G=angle R-angle S

wherein angle R=the angle whose tangent is equal to

$$(.675\sqrt{10B} \times \sqrt{\text{Pass dia.}})$$

10 and

Angle S=an angle of $\frac{10}{B}$ degrees

and in which

B=the height of the lug

and

Pass diameter=the outside diameter of the rolls minus twice the depth of pass (depth of the pass groove).

15 *Example for 1 1/4 inch square nominal size*

$$\text{Pass dia.} = 14.986 - (2 \times .641)$$

or 14.986 - 1.282, or 13.704 inches.

20 Height of lug=.085 inch (see example above)

Angle R=the angle whose tangent is equal to

$$(.675\sqrt{.85} \times \sqrt{13.704})$$

25 or $(.675 \times .922 \times 1.924)$ or 1.1974 (tangent of angle R), or $50^\circ 8'$.

Angle S= $\frac{10}{.085}$ degrees

30 or 117.6° or $1^\circ 11'$.

35 Angle G=angle R-angle S

or $(50^\circ 8') - (1^\circ 11')$, or $48^\circ 57'$.

40 In utilizing the above formulas, the height of the lug is the maximum permissible, whereby lugs of the height determined by the formula, as well as lugs of less height, may be employed without suffering wiping or damage.

45 Similarly, in utilizing the formula for angle G, it is important to know that angles less than those determined by the formula cannot be used without suffering wiping or damage, wherefore it follows that angles greater than those determined by the formula may be employed. These formulas are correct and workable for bars of different sizes and can be employed in rolling all sizes required for a full commercial range, varying from the smallest sizes around $3/8$ inch up to $1 \frac{1}{4}$ inches, and larger.

50 In considering the significance of angle G, it should be understood that the limitation imposed thereby is applicable only to the lead angle of the lug on the bar for the reason that during the rolling operation the advancing movement of the bar when leaving the rolls tends to overtake the lug-forming portions of the rolls, and hence the angularity of the cooperating portions of the roll and lug must be such as to permit a free passage if wiping and damage are to be avoided. By the "lead angle" the front or advancing face of the lug is referred to. On this account, the rear or trailing faces of the lugs on the bar may be of any desired angle. In the present illustration, the trailing faces of the lugs have the same angularity as the leading faces for the purpose of 55 uniformity in both directions, but such is not essential to this invention.

60 Referring now to Figures 5 to 10, inclusive, it will be noted that the bar produced by the rolls of this invention comprises a solid, substantially 65 cylindrical body or core section 40 provided with

diametrically opposed parallel ribs 41, 42 extending longitudinally of the bar, as well as diametrically opposed sets of spirally disposed lugs 43, 44 located between the ribs 41 and 42 and joining the same at their ends. The lugs 43 and 44 are each segments of a spiral, and one set is a segment of a right-hand spiral and the other set a segment of a left-hand spiral, whereby the adjacent ends of the lugs of the two sets, which terminate at the locations of the ribs 41 and 42, are inclined in opposite directions with respect to a plane normal to the axis of the bar. Thus viewing the bar as in Figure 6, the spirally disposed lugs 43 and 44 converge from the left-hand end toward the right-hand end of the bar as shown, whereas when the bar is rotated through 180° the lugs will converge in the opposite direction.

The lugs 43 and 44 have inclined faces as determined by angle G (see Figures 10 and 11) or any angle greater than angle G, and at their bases are provided with concaved fillets, as shown at F in Figure 10. Similar fillets, shown at 46, are provided at the base of the longitudinally extending parallel ribs 41 and 42 so as to eliminate sharp corners or pockets.

It is apparent that bars of this construction will be produced when stock of suitable configuration is passed through a mill such as that shown in Figure 1 and the rolls are constructed in the manner described above. In rolling the bar, it is preferable to effect approximately a 25% reduction in the finishing pass of the rolling operation, which not only causes the lugs to be formed as indicated but also the ribs 41 and 42 to be extruded laterally into the space between the rolls. This operation results in the bar having ribs 41 and 42 of substantially the same height as the lugs themselves. When the lugs are inclined in opposite spirals, as above indicated, all tendency toward twisting of the bar is eliminated during the rolling operation and a satisfactory straight product is produced. Furthermore, due to the rolling action, the final pitch of the lugs on the finished bar will be greater than the pitch of the lug-forming grooves provided in the forming rolls.

While the invention is not limited to rolls productive of bars having any specific dimensions of the core, lugs, or ribs, other than as hereinabove indicated by the formula, when wiping is to be avoided, the following specifications and proportions as to certain sizes of ribs are here given merely by way of example, which when followed will provide satisfactory reinforcing bars of light, medium, and heavy weights, respectively, that is to say, bars having the same weight per foot, namely, .376 pound as a plain round $\frac{3}{8}$ inch diameter bar; bars having the same weight per foot, namely, 2.44 pounds as a plain round $\frac{7}{8}$ inch diameter bar; and bars having the same weight per foot, namely, 5.313 pounds as a $1\frac{1}{4}$ inch square diameter bar.

In accordance with the above example of the lighter weight bar, the core 40 is .354 of an inch diameter; the depth, indicated at B, of the depressions framed by the ribs and lugs, .038 of an inch; the width, indicated at C, of the ribs at their circumferential surfaces .040 of an inch; the width, indicated at D, of the lugs at their circumferential surfaces, .031 of an inch; the pitch, indicated at E, .203 of an inch; the radius, indicated at F, of the lug fillets, $\frac{3}{32}$ of an inch; and the radius indicated at F' of the rib fillets, $\frac{1}{16}$ of an inch.

In the case of the above example of a medium weight bar, the core 40 is .825 of an inch dia-

ter; the depth B, .061 of an inch; the width C, .080 of an inch; the width D, .060 of an inch; the pitch E, .375 of an inch; the radius F of the lug fillets, $\frac{1}{16}$ of an inch; and the radius F' of the rib fillets, $\frac{1}{16}$ of an inch.

In the case of the above example of a heavy bar, the core 40 is 1.360 of an inch diameter; the depth B, .085 of an inch; the width C, .100 of an inch; the width D, .080 of an inch; the pitch E, .603 of an inch; the radius F of the lug fillets, $\frac{3}{32}$ of an inch; and the radius F' of the rib fillets $\frac{1}{16}$ of an inch.

The fillets are provided primarily for the purpose of avoiding pockets or corners which could not be readily reached and filled by concrete when the same is used for reinforcing purposes.

Whereas the sides of the lugs have been referred to as "angular" as determined by the angle G, it is apparent that the fillets may be enlarged to give a general concave configuration to the sides of the lugs, provided, however, that the effective angularity thereof does not exceed the angle determined by angle G.

As previously pointed out, angle G as determined by the formula, marks the limit of approach to the vertical that may be utilized without wiping, and in consequence greater angles or concavities for fillets which come within the effective rule of the formula may also be employed without suffering the damage of wiping during the bar-forming process.

By virtue of the fact that the lug-forming grooves on the rolls are inclined in relation to the axis of the bar, all trapping of steam or water between the rolls during the bar-forming operation is avoided, with the manifest advantage of avoiding spalling or similar damage to the rolls and lugs.

As shown in Figures 8 and 9, the diametrically opposed sets of lugs 43' and 44' may be arranged in staggered relation instead of meeting relation as shown in Figure 6. The degree of displacement may vary in any particular case.

By virtue of the spiral disposition of the lugs 45 in the form of bar illustrated in Figure 6, as well as that illustrated in Figure 8, the bars so constructed will have the same cross-sectional area in every transverse section, provided the lead of the lugs is sufficiently great in relation to their pitch. This fact adds greatly to the ease of rolling and, in addition, is productive of a bar having greater uniformity of strength throughout its length.

In the cases of the bars of particular sizes mentioned in the above-stated examples, the leads of the lugs of the several bars as set forth are the minimum permissible if the bar is to have the same cross-sectional area throughout its length. However, the pitches may be made greater than specified in the above examples and still maintain a uniform cross-sectional area throughout the length of the bar.

It will usually be desirable to provide a bar having the highest permissible lugs and the steepest possible angle on the leading face of the lug. Bars so constructed have the maximum bonding effect when embedded in concrete. Consequently, the first formula given above may be employed for determining the maximum height of the lugs 70 for a bar of a particular size, and thereafter the second formula may be employed to determine the steepest permissible angle for the leading faces of such lug. In this manner undesirable wiping or damage to the bar and rolls may be avoided. Of course, if lug heights less than the

maximum are desired, the second formula may still be employed for providing a leading side face on the lugs of the greatest possible steepness.

It is apparent that the bar produced by the rolls of this invention will possess all of the properties described and claimed for it in applicant's said continuation-in-part application Serial No. 537,125 and its parent application Serial No. 501,553.

Whereas the rolls of this invention have been illustrated as having the lug-forming grooves disposed in opposite directions, or, in other words, as segments of spirals of opposite hand, this invention extends to rolls having lugs of different construction and arrangement, such as, for instance, rolls having opposed sets of lugs inclined or spiraled in the same direction. In all events, it will be apparent that a new and useful method is provided, together with improved rolls, whereby the pass grooves which extend substantially 180° of the diameter of the bar to be formed are provided with lug-forming grooves cut into the sides and the base of the pass grooves, and further that the rolls may be utilized as the final finishing rolls in the usual rolling mill for production of bars of superior construction and quality.

I claim:

1. The process of forming a pair of rolls for rolling mill or the like, which comprises cutting a circumferential pass groove of substantially semicircular cross-section in each of said rolls in such position that said grooves cooperate to form a pass opening when said rolls are associated in operative position, thereafter rotating each of said rolls on its axis, and during such rotation rotating a spirally disposed series of cutting elements on its axis while said last-named axis is disposed parallel to but outside of the tangent to the surface of the roll being processed at the location of the center of the pass groove therein, advancing said series of rotating cutting elements bodily toward the axis of said roll while maintaining the axis of said series of rotating cutting elements parallel to said tangent and thereby cutting in each of the sides of said pass groove a series of notches, each equally spaced around the circumference of said pass groove and continuing the advancement of said series of rotating cutting elements while maintaining the same parallel to said tangent, until said series of cutting elements has extended said notches to the base of said pass groove and formed in said pass groove a series

of lug-forming grooves extending generally transversely of said pass groove.

2. The process defined in claim 1, further characterized in that the series of lug-forming grooves of one of the rolls of each pair of rolls is cut by rotating the spirally disposed series of cutting elements in contact therewith, as defined, of one hand, and the series of lug-forming grooves of the other of said rolls of each pair of rolls is cut by rotating the spirally disposed series of cutting elements in contact therewith, as defined, of the opposite hand.

3. The process defined in claim 1, further characterized in that the series of lug-forming grooves of one of the rolls of each pair of rolls is cut by 15 rotating the spirally disposed series of cutting elements in contact therewith, as defined, of the one hand and while rotating said roll in one direction, and the series of lug-forming grooves of the other of said rolls of each pair of rolls is cut by rotating the spirally disposed series of cutting elements in contact therewith, as defined, of the opposite hand and while rotating the roll in a direction opposite to that of the first roll of said pair of rolls.

4. The process defined in claim 1, further characterized in that the rotation of said rolls is synchronized with the rotation of the spirally disposed series of cutting elements in cutting association therewith, whereby a predetermined number of substantially uniformly spaced lug-forming grooves are formed in the pass grooves of said rolls extending entirely around the circumferences thereof, respectively.

5. The process defined in claim 1, further characterized in that the pitch of said spirally formed grooves is determined by enlarging the pitch of the lugs to be provided on the finished bar to be rolled thereby, by the shrinkage of said bar during cooling after rolling, and diminishing the sum thereof by the elongation of said bar during the rolling operation.
